(57) **CLAIM**

The ornamental design for an umbrella solar panel cap and USB charging station, as shown and described.

DESCRIPTION

FIG. 1 is a top, front and left side perspective view of an umbrella solar panel cap and USB charging station showing our new design in environmental use;

FIG. 2 is a front view of the umbrella solar panel cap with USB charging station;

FIG. 3 is a left side elevation view of the umbrella solar panel cap with USB charging station, with right side elevation view being a mirror image of FIG. 3;

FIG. 4 is a rear view of the umbrella solar panel cap with USB charging station;

FIG. 5 is a top plan view of umbrella solar panel cap with USB charging station; and,

FIG. 6 is a bottom plan view of the umbrella solar panel cap with USB charging station.

The broken lines shown represent unclaimed subject matter and form no part of the claimed design.
